UNITED STATES PATENT OFFICE.

AUGUST K. SCHULTE, OF PHILADELPHIA, PENNSYLVANIA, ASSIGNOR OF
ONE-HALF TO JOHN J. WALTER, OF SAME PLACE.

DESIGN FOR A MOUTHPIECE.

SPECIFICATION forming part of Design No. 33,412, dated October 23, 1900.

Application filed September 4, 1900. Serial No. 29,012. Term of patent 7 years.

To all whom it may concern:

Be it known that I, AUGUST K. SCHULTE, a citizen of the United States, residing at Philadelphia, in the county of Philadelphia and 5 State of Pennsylvania, have invented and produced a new and useful Design for Mouthpieces, of which the following is a specification.

This invention relates to a new design for a mouthpiece for cigar and cigarette holders, 10 pipes, &c. I have illustrated the same in the accompanying drawings, in which—

Figure 1 is a side view. Fig. 2 is a central longitudinal section, and Fig. 3 is an end view.

Referring to the drawings by numerals of 15 reference, 1 is the circular end of the device, having perforations 2 therein arranged in con-

centric circles. A rounded bead is arranged about the end 1, and a cylinder 4 extends from said bead. The inner end of this cylinder is inclined inward, as at 5, and terminates in a 20 circumferentially - reduced cylindrical portion 6.

What I claim is—

The design for a mouthpiece, substantially as herein shown and described. 25

In testimony whereof I affix my signature in presence of two witnesses.

AUGUST K. SCHULTE.

Witnesses:

JAMES MARTIN,
CHARLES KAISER.
